UNITED STATES PATENT OFFICE.

ARTHUR J. BENNETT, OF CAMBRIDGE, OHIO.

DESIGN FOR A COMBINED CENTERPIECE AND FLOWER-HOLDER.

49,384.

Specification for Design.

Patented July 18, 1916.

Application filed February 17, 1916. Serial No. 78,996. Term of patent 7 years.

To all whom it may concern:

Be it known that I, ARTHUR J. BENNETT, a citizen of the United States, residing at Cambridge, in the county of Guernsey and State of Ohio, have invented a new, original, and ornamental design for a Combined Centerpiece and Flower-Holder, of which the following is a specification, reference being had to the accompanying drawing, forming part thereof.

Fig. 2 is a top plan view thereof; Fig. 3 is a central cross-section, showing the flower holder in side elevation; and Fig. 4 is a bottom plan view.

I claim:

The ornamental design for a combined centerpiece and flower holder, as shown.

ARTHUR J. BENNETT.

Witnesses:
